UNITED STATES PATENT OFFICE

162,132

STEPLADDER

Doran R. Dole, Russell, Kans.

Application June 12, 1950, Serial No. 10,468

Term of patent 14 years

(Cl. D15—8)

To all whom it may concern:

Be it known that I, Doran R. Dole, a citizen of the United States, residing at Russell, in the county of Russell and State of Kansas, have invented a new, original, and ornamental Design for a Stepladder, of which the following is a specification, reference being had to the accompanying drawing, forming a part hereof.

The figure represents a perspective view of a stepladder embodying my design.

I claim:

The ornamental design for a stepladder, substantially as shown.

DORAN R. DOLE.
